UNITED STATES PATENT OFFICE.

HUGO F. HOEFLER, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC-PRINT SQUARE.

1,183,977.

Specification of Letters Patent. Patented May 23, 1916.

Application filed November 14, 1911. Serial No. 660,231.

To all whom it may concern:

Be it known that I, Hugo F. HOEFLER, of Rochester, in the county of Monroe and State of New York, have invented certain 5 new and useful Improvements in Photographic-Print Squares; and I do hereby declare the following to be a full, clear, and exact description of the same, reference being had to the accompanying drawings, 10 forming a part of this specification, and to the reference-numerals marked thereon.

My present invention relates to photography and more particularly to photographic printing, and it has for its object 15 to provide a simple device capable of being cheaply produced for squaring or truing up photographic prints prior to mounting the same, the square being also adapted to be used on the mounts and mats provided for 20 the print as well.

Further objects of the invention are to render the square capable of defining parallelograms and more particularly rectangles of any desired dimensions and to adapt the 25 square to being folded conveniently and securely within small compass.

To these and other ends the invention consists in certain improvements and combinations of parts all as will be hereinafter more 30 fully described, the novel features being pointed out in the claims at the end of the specification.

In the drawings: Figure 1 is a top plan view of a square constructed in accordance 35 with and illustrating one embodiment of my invention; Fig. 2 is a section on the line *a—a* of Fig. 1, and Fig. 3 is a section on the line *b—b* of Fig. 1, both sectional views being enlarged.

Similar reference numerals throughout 40 the several figures indicate similar parts.

In order that the square may completely define an inclosed space forming the area of the print it is made of two angle squares 45 A and B, the arms 1 and 2 and 3 and 4, respectively, of which overlap each other at 5 and 6, while one unit of each pair also overlaps a unit of the other pair, as at 7 and 8, forming in the present instance an inclosed 50 parallelogram C. The arms of each angle A and B are detachably secured together in rigid relationship preferably in the manner indicated in Fig. 3 which illustrates the arms 3 and 4 of the angle square B and to 55 this end, the arm 4 is provided in the region

of the overlapping portion 6 with recesses 9 with which engage pins or projections 10 that, in the present instance extend through registering openings 11 in the arm 3 and are secured to a removable plate 12. Extending 60 through the latter and both arms is a bolt 13 having a head 14 engaging on one face of one arm and carrying a threaded nut 15 at the other end which is tightened down against the plate 12 to hold the projections 65 10 in the recesses of the arm. These recesses are so spaced and arranged with reference to the angle of the arms 3 and 4 that the bolt and plate 12 may be removed and the arms detached from the relation of Fig. 70 1 and laid one on top of the other to extend coincidently, with the apertures 9 and 11 in a reverse register. The plate 12 and bolt 13 may then be replaced in the same manner as before and the square thus maintained in a 75 folded relation in which it is secure and compact.

In order to contract or enlarge the area C, the two angle squares A and B are made to slide upon each other in two directions at 80 right angles to each other so that either or both dimensions of the area may be varied and to this end, all of the arms are provided with guides constituted in the present instance by central longitudinal slots 16 and 85 at the intersecting portions 7 and 8 bolts 17 are passed through the arms within the slots to serve as securing devices. A head 18 on each bolt engages the outer face of one arm, being the arm 1 in Fig. 2, while on the other 90 side of the intersecting portion 7, for instance, it is provided with a plate in the form of a spider 19, engaged by a threaded thumb nut 20. A spring 21 is suitably interposed between the thumb nut and the 95 spider for purposes later described. The spider 19 embodies suitably spaced fingers or projections 22 and these engage the slotted guides 16 of each arm laterally of the bolt 17 and on opposite sides of the intersecting 100 arm, one pair of oppositely arranged fingers being, of course, in a plane lower than that of the other in order to reach the under arm.

The bolt 17 is locked against rotation relatively to its extension or spider 19, as by the formation of a flattened portion 23 thereon passing through a corresponding opening in the spider and when it is desired to adjust the square to change the size of the 110

area C, the nut 20 is loosened. This does not release the intersecting arms from engagement they being still held by the spring 21, but with a yielding pressure so that one 5 arm may be slid upon the other to any location desired. During this operation the fingers 22 traveling in the guides 16 rigidly maintain the true angular relation of the arms, being likewise held in place by the 10 pressure of the spring. The thumb nut 20 is tightened after the adjustment is made clamping the spider and both arms tightly together and the square is ready for use. Of course, both of the bolts 17 are removable, 15 by detaching the thumb nuts 20 therefrom, but may be again applied (simply to keep the parts together) when the arms are assembled in the folded relation before described.

20 If desired, the arms of either angle square A or B, or one arm of each, representing two dimensions of the area C, may be graduated, as indicated, so that the dimensions of the latter in a given instance may be pre- 25 determined.

The device of my invention will suggest itself for other similar uses outside of the photographic art, but I have described it in this connection as the present embodiment was designed primarily for truing up 30 photographic prints.

I claim as my invention:

1. In a square, the combination with a pair of crossed arms provided with slots forming guides, of a spider comprising a 35 plate lying flat against and spanning the crossed portion of the arms and provided with relatively rigid and inseparable fingers coöperating with the slot in each arm on opposite sides of the other arm, said fingers 40 proceeding downwardly from the plate to the planes of the respective arms and thence longitudinally within the slots to lie flush with the face of the arm, and a bolt extending centrally through the spider and through 45 the slots of both arms for securing said parts together.

2. In a square, the combination with a pair of arms each having two separate recesses therein so positioned relatively to each other and angularly to the arm as to adapt the recesses of one arm to respectively register with those of the other when the arms are either disposed angularly to each other or coincidently in superposed relation, and means comprising relatively fixed projections extending through the recesses for securing the arms together in either position. 50 55
